CLAIM

The ornamental design for a tie standoff, as shown and described.

DESCRIPTION

FIG. 1 is a top perspective view of a tie standoff, shown in use with a tie.

FIG. 2 is a top perspective view of the tie standoff of FIG. 1, shown alone.

FIG. 3 is a bottom perspective view of the tie standoff of FIG. 2.

FIG. 4 is a top view of the tie standoff of FIG. 2.

FIG. 5 is a front view of the tie standoff of FIG. 2.

FIG. 6 is a rear view of the tie standoff of FIG. 2.

FIG. 7 is a bottom view of the tie standoff of FIG. 2.

FIG. 8 is a first side view of the tie standoff of FIG. 2; and, FIG. 9 is an opposite side view of the tie standoff of FIG. 2. The tie shown in broken lines in FIGS. 1 and 10 is shown for environment and forms no part of the claimed design.

1 Claim, 4 Drawing Sheets
